VENDING MACHINE CABINET

Walter E. Moore, Bel-Nor, Mo., assignor to National Vendors, Inc., St. Louis, Mo., a corporation of Missouri

Application August 16, 1954, Serial No. 31,877

Term of patent 7 years

(Cl. D52—3)

FIG. 2.

FIG. 1.

FIG. 3.

To all whom it may concern:

Be it known that I, Walter E. Moore, a citizen of the United States and a resident of Bel-Nor, St. Louis County, Missouri, have invented a new, original, and ornamental Design for a Vending Machine Cabinet, of which the following is a specification, reference being had to the accompanying drawings, forming part hereof, in which:

Fig. 1 is a front elevation of a vending machine cabinet embodying my new design;

Fig. 2 is a plan view of Fig. 1;

Fig. 3 is a side elevation of Fig. 1; and,

Fig. 4 is a rear elevation of Fig. 1.

I claim:

The ornamental design for a vending machine cabinet, substantially as shown.
